(**) Term: **14 Years**

(57) **CLAIM**

(21) Appl. No.: **29/144,917**

The ornamental design for a heating, ventilating and air conditioning system controller, as shown and described.

(22) Filed: **Jul. 12, 2001**

DESCRIPTION

(51) LOC (7) Cl. **10-04**

FIG. 1 is a perspective view of the heating, ventilating and air conditioning system controller showing our new design;

(52) U.S. Cl. **D10/50**

FIG. 2 is a front view thereof;

(58) Field of Search D10/49, 50; 200/343;

FIG. 3 is a left side view thereof;

236/46 R, 47, 49.3, 51, 84, 94; 361/680,

FIG. 4 is a right side view thereof; and,

681; 400/495

FIG. 5 is a top view thereof.
